United States Patent Office

Des. 178,654
Patented Sept. 4, 1956

178,654

MOCCASIN

Ely Freedman, Atlanta, Ga., assignor to Greyshaw of Georgia, Inc., Atlanta, Ga.

Application March 23, 1956, Serial No. 40,739

Term of patent 3½ years

(Cl. D7—7)

I claim:

The ornamental design for a moccasin as shown.
